UNITED STATES PATENT OFFICE.

JOHN H. ARGYLL, OF NEWBURYPORT, MASSACHUSETTS, ASSIGNOR TO THE TOWLE MANUFACTURING COMPANY, OF SAME PLACE.

DESIGN FOR A SPOON, FORK, &c.

SPECIFICATION forming part of Design No. 19,301, dated September 10, 1889.

Application filed July 15, 1889. Serial No. 817,643. Term of patent 7 years.

To all whom it may concern:

Be it known that I, JOHN H. ARGYLL, of Newburyport, in the county of Essex and State of Massachusetts, have invented and produced a new and original Design for Spoons, Forks, and other Articles of Flatware, of which the following is a full, clear, and exact description, reference being had to the accompanying photograph, which forms part of this specification, and which represents my new design as applied to a spoon.

The feature of my design consists in the ornamentation of the face or front portion of the handle of the article, the same, as shown in the accompanying photograph, comprising the representation of a serpentine-like figure *b*, having scroll-like ornate *c d e* and circular ornaments *h i* appearing to jut from reverse sides of it. This serpentine-like figure *b* conforms in shape above to the upper marginal portion of the handle, where it is ornamented by further scroll-like figures *k*,

and appears to join a scallop-like figure *l*, that appears to connect it with a further scroll-like figure *m*. Below this serpentine-like figure *b* are a series of circular ornaments *n*, appearing to terminate beneath in a leaf-like figure *o*.

I claim—

The within-described design for spoons and other articles of flatware, consisting of a serpentine-like figure upon the handle of the article, having scroll-like and circular ornate appearing to jut from reverse sides of it, a scallop-like figure appearing to join a further scroll-like figure, and circular ornate appearing to terminate in a leaf-like figure, as illustrated in the accompanying photograph.

JOHN H. ARGYLL.
